UNITED STATES PATENT OFFICE.

JOHN CAMPER HOOPER, OF BALTIMORE, MARYLAND.

DESIGN FOR A VALVE-CASING FOR LOCOMOTIVE SANDER APPARATUS.

SPECIFICATION forming part of Design No. 33,749, dated December 18, 1900.

Application filed November 19, 1900. Serial No. 37,071. Term of patent 14 years.

To all whom it may concern:

Be it known that I, JOHN CAMPER HOOPER, a citizen of the United States, residing at Baltimore, in the State of Maryland, have invented and produced a new and original Design for a Valve-Casing for Locomotive Sander Apparatus, of which the following is a specification.

Reference is to be had to the accompanying drawings, illustrating my design, in which—

Figure 1 is a side elevation of the valve-casing for locomotive sander apparatus. Fig. 2 is a bottom plan view of same. Fig. 3 is a side elevation reversed looking from the rear side of Fig. 1. Fig. 4 is a transverse section on a line through the center.

As illustrated in the drawings, the design consists of a straight tubular main portion *a*, at whose ends appear exteriorly-screw-threaded nipples *b* of slightly-smaller diameter than said main portion, and between said ends appear two short tubular branches *c*, parallel

with each other and of equal size and extending at right angles from the side of the main tubular portion *a*. A tubular nipple *d* extends from the side of the main tubular portion *a* at right angles to the said two tubular branches *c* and between them. Said nipple *d* is diametrically larger than the main tubular portion, whereby two segmental swells *e* appear, one projecting on each side of the main tubular portion, and the end of the large nipple *d* is exteriorly screw-threaded.

I claim—

The design for a valve-casing for locomotive sander apparatus, herein shown and described.

In testimony whereof I affix my signature in the presence of two witnesses.

JOHN CAMPER HOOPER.

Witnesses:

CHARLES L. VIETSCH,
F. S. STITT.
